TRAVELING WAVE TYPE TUBE AND METHOD OF MANUFACTURE

Bernard Kleinman, New York, N.Y., assignor to Radio Corporation of America, a corporation of Delaware

Filed Apr. 11, 1958, Ser. No. 727,955

6 Claims. (Cl. 315—3.5)

This invention relates to an improved traveling wave type tube and method of assembling the same, and in particular to a structure and method for mounting a helix structure within the tube.

In the usual traveling wave type tube an electron beam is projected adjacent to an elongated signal wave delay line in the same direction and at approximately the same velocity as signal waves traveling along the line in order to achieve amplification of the signal waves. The delay line, which is usually in the form of a relatively long, slender conductive helix, must be rigidly supported to achieve close adjacency between the beam and the line. To this end the helix is usually either (1) mounted in a snug fit within an elongated, non-conductive envelope or, (2) supported in coaxial spaced relation with respect to the envelope by means of three equally spaced insulating rods positioned around the helix. However, such helix support arrangements have several disadvantages. For example, in the first named arrangement the close fit required between the helix and the envelope sometimes results in fabricating difficulties and breakage of the usually fragile envelope. In addition, the dielectric loading of the helix is very high.

Bianculli Patent 2,806,170 relates to a form of mounting the helix, according to the second arrangement mentioned above, in which the helix and ceramic rods are assembled together within the envelope by means of clamp rings and resilient members which are disposed between the rods and the clamp rings and resiliently press the rods against the helix.

An object of the present invention is to provide an improved resilient clamping means in the Bianculli type of helix-rod assembly.

A further object is to provide a novel method of mounting a helix assembly within the envelope of a traveling wave type tube.

The foregoing and other objects are achieved in accordance with the method of the invention by providing a resilient tubular metallic clamp which is to be clamped about an assembly of support rods arrayed about a helix. This clamp is initially circular with a cross sectional area which is greater than that of the helix assembly to be inserted therein but with a normal diameter which is less than that of the circle circumscribing said helix assembly. To produce the clamped assembly, the clamp is first distorted by forces applied at a number of points corresponding to the number of rods so as to produce a geometrical configuration more nearly identical to that of the assembly rods and helix. The rods and helix are inserted into the distorted clamp with the rods intermediate the points of application of the forces. Upon removal of the distorting forces, the clamp restores itself to nearly its original circular shape, and in doing so compresses the rods and helix into a rigid assembly.

2

Preferably, more than one clamp is used so that the helix is supported along a substantial part of its length.

In the drawing:

Fig. 1 is a partially cut away longitudinal sectional view of a traveling wave type tube embodying the invention;

Fig. 2 is a transverse sectional view taken on line 2—2 of Fig. 1;

Fig. 3 is a transverse view of a resilient member and 10 a helix sub-assembly supported in a clamping structure used in practicing the method of the invention;

Fig. 4 is a partially cut-away longitudinal sectional view of a traveling wave type tube embodying another form of the invention; and

Fig. 5 is a transverse sectional view taken on line 5—5 of Fig. 4.

The traveling wave type tube shown in Figs. 1 and 2 is known as a backward wave oscillator and comprises a tubular glass envelope 10 of circular cross section containing an electron gun 12 at one end of the tube, a collector electrode 14 at the opposite end of the tube, and a conductive helix or helical conductor 16 intermediate the electron gun 12 and the collector electrode 14. The structural and operational details of the electron gun 12 and the collector electrode 14 are well understood and will therefore not be further described, except to note that they should be designed to project and collect an electron beam along the axis of the tube.

The helix 16 is mounted coaxially with the envelope 30 10 between three insulating rods 18, of glass or ceramic, for example, extending longitudinally inside the envelope 10 parallel to the common axis of the envelope 10 and the helix 16. The helix is maintained in desired axial alignment with the electron gun 12 and the collector electrode 14 by means of tubular projections 20

and 22 of, respectively, the electron gun 12 and collector electrode 14 and by a plurality of resilient metallic tubular clamps or sleeves 24 and 26 according to the invention, the clamps being described in detail below. The

35 end portions of each insulating rod 18 are disposed around and snugly engage the tubular projections 20 and 22 and are fixed in position with respect to the projections 20 and 22 by means of the clamps 24 and 26,

which cause the insulating rods 18 to grip the projections 20 and 22. The helix 16 is adapted to be coupled to an external load by means of an antenna conductor extension 23 and a coupling sleeve 25.

The method of force fitting the clamps 24 and 26 around the insulating rods 18 is illustrated in Fig. 3.

50 A suitable clamping fixture 28 having an overall length generally the same as the helix 16 and insulating rods 18 is made up of a U-shaped base 30 and four upstanding supports 32 mounted on the legs of the U, there being two supports 32 at each end of the base. A hori-

55 zontal pressure plate 34 is slidably mounted across the tops of the supports 32, with the supports 32 protruding through holes in the plate 34 so that the plate 34 can be moved up or down.

In carrying out the method of the invention, two metal

60 rods 36 are first placed in the corners of the U-shaped base 30. The clamps 24 and 26 are placed on the metal rods 36 and spaced apart to conform to the position they

will assume in the finished tube. A third metal rod 36 is placed on top of the clamps and the plate 34 is

65 brought into contact with this rod 36. The underside of the plate 34 has a notch 38 therein to contain the third rod 36. The rods 36 and base 30 are suitably di-

mentioned so that the rods 36 are arrayed about the clamps 24 and 26 at equal intervals, in this case 120° apart.

Prior to the application of force on the plate 34, the clamps 24, 26 have a circular cross section such that their inside diameter is slightly less than the diameter of the circle defined by the outer extremities of the insulating rods 18 disposed around the helix 16. Stated differently, the transverse extent of the inside surfaces of the clamps 24, 26 is less than the transverse extent of the generally triangular figure bounded by the insulating rods 18, but the circular area defined by the inside surfaces of the clamps 24, 26 is greater than the area of said generally triangular figure.

Downward force applied to the plate 34 is transmitted through the equally spaced metal rods 36 to the points of the clamps 24, 26 in contact with the metal rods 36. These points are flexed inwardly, but the portions of the clamps lying midway between the metal rods 36 are bowed outwardly, so as to distort the clamps 24, 26 into a shape which more nearly conforms to, but is of greater size than, the triangular shape of the helix 16 and insulating rod 18 sub-assembly, as shown in dotted outline in Fig. 3. The force applied to the clamps 24, 26 is such that the elastic limit of the clamp metal is not exceeded. Suitable high-tensile strength metal, such as steel, may be used for the clamps.

While the clamps 24, 26 are thus distorted, the sub-assembly of helix 16 and insulating rods 18, supported on suitable mandrel, is inserted within the clamps 24, 26, with the bowed out portions thereof providing sufficient clearance for the insulating rods 18. Next, the mandrel is removed, and the electron gun 12 and collector electrode 14 are mounted at opposite ends of the insulating rods 18 by inserting the tubular projections 20 and 22 between the rods 18.

Upon removing the force from the plate 34, the clamps 24, 26 spring back to nearly their original shape, and in doing so clamp the insulating rods 18 to compress them against the helix 16 into a rigid sub-assembly. In addition, the ends of the insulating rods 18 are compressed about the projections 20, 22 to fix them in position.

Thereafter, the assembled elements are sealed vacuum tight with the glass envelope 10.

It is noteworthy that the method of assembling tube elements according to the invention as above described is characterized by its simplicity, because of the lack of any of the more cumbersome means for joining parts, such as welds, brazes, or other metal flow processes. Practically all the elements are held in fixed relation with each other solely by compression forces.

Figs. 4 and 5 show a traveling wave type amplifier tube provided with clamps which constrain the helix sub-assembly according to the invention and which serve also as parts of the envelope structure. In this embodiment, the envelope comprises three resilient metallic tubular clamps 40, 42, 44, joined end-to-end to two intermediate insulating rings 46, 48, which may be ceramic, by brazing. The central clamp 42 is rather long and surrounds the length of the helix 50 except for a few turns at each end of the helix 50. These few turns of the helix 50 are surrounded, with some clearance, by the ceramic rings 46, 48, which serve as dielectric windows to permit the introduction and extraction respectively of electromagnetic energy into and from the helix 50.

In accordance with the invention, the long central clamp 42 is clamped around the major central portion of the insulating rods 52. The two shorter clamps 40, 44 are clamped around the ends of the insulating rods 52. The ends of the rods 52 in turn are clamped about projections 54, 56 of the electron gun 58 and collector 60, respectively. Two antenna conductors 62, 64 are connected between the ends of the helix 50 and the ends of the central clamp 42.

In fabricating the tube structure of Figs. 4 and 5, ceramic rings 46, 48 and metal clamps 40, 42, 44 are assembled end to end with each clamp being held in a fixture of the kind shown in Fig. 3. The clamps 40, 42, 44 are then distorted in the manner previously described, the helix 50 and insulating rods 52 inserted within the clamps and ceramic rings 46, 48, and upon removal of the distorting force, the clamps 40, 42, 44 compress about the helix assembly. The helix assembly is then removed from the fixtures, and the clamps 40, 42, 44 and ceramic rings 46, 48 are brazed together. Tubular envelope portion 66 and collector 60 are then sealed to the clamps 40 and 44 at the ends of the tube to complete the envelope assembly.

15 What is claimed is:

1. An electron discharge device comprising an envelope including a resilient tubular metallic portion, and a substantially rigid elongated polygonal conductive helix sub-assembly disposed within said envelope portion, said envelope portion encircling, engaging and clamping said helix sub-assembly into a rigid assembly therewith.

2. An electron discharge device of the traveling wave type comprising an envelope including a resilient tubular metallic portion, an elongated conductive helix within said envelope portion, and an array of mutually spaced insulating rods surrounding and engaging said helix, said envelope portion encircling, engaging and compressing said rods against said helix.

3. A method of making a helix assembly, including the steps of providing an elongated substantially rigid sub-assembly of a helix surrounded by an array of mutually-spaced longitudinally-extending support rods engaging said helix in a predetermined non-circular configuration, providing a resilient tubular metallic member normally shaped to have a cross-sectional area greater than but a transverse extent less than said configuration, applying force to distort said resilient member within its elastic limit to increase and decrease its transverse extent in different portions thereof and make it conform more nearly to said configuration, inserting said sub-assembly within said distorted member, and removing said force thus permitting said tubular member to be restored nearly to its original shape and brought into clamping engagement with said sub-assembly.

4. A method of assembling a conductive helix assembly within the envelope of an electron discharge device, said method comprising fixing a resilient tubular metallic envelope portion within a support structure, subjecting said envelope portion to distortion force within its elastic limit for increasing the inside transverse extent of said envelope portion along certain portions thereof and decreasing the inside transverse extent along other portions, inserting a substantially rigid elongated polygonal conductive helix assembly having

large and small transverse dimensions within said envelope portion with the large dimensions of said assembly fitting within said certain portions of increased inside transverse extent and the small dimensions fitting within said other portions, and then removing said force thereby permitting said envelope portion to restore itself and engage and clamp said assembly into a unitary structure with said portion.

5. The method described in claim 4 and wherein said helix assembly comprises an elongated conductive helix and a plurality of insulating rods external to and engaging said helix longitudinally thereof, and wherein each of said rods is disposed within one of the enlarged transverse extents of said envelope portion.

6. A method of making helix assembly, including the steps of fixing a resilient tubular metallic member within a support structure, subjecting said member to distortion force within its elastic limit for increasing the inside transverse extent of said member along certain portions thereof and decreasing the inside transverse extent along other portions, inserting a substantially rigid elongated

75

polygonal helix assembly having large and small transverse dimensions within said member with the large dimensions of said assembly fitting within said certain portions of increased inside transverse extent and the small dimensions fitting within said other portions, and then removing said force thereby permitting said member to restore itself and engage and clamp said helix assembly into a unitary structure.
